United States Patent Office

Des. 185,767
Patented July 28, 1959

185,767

URINAL

Harry P. McCann, Seattle, Wash.

Application March 17, 1958, Serial No. 50,068

Term of patent 14 years

(Cl. D4—5)

Fig. 1

Fig. 2

Fig. 3

Fig. 1 is a perspective view of a urinal embodying my new design.

Fig. 2 is a front view of the same.

Fig. 3 is an end view of the same.

The undisclosed end of the urinal is substantially the same in appearance as the end shown.

I claim:

The ornamental design for a urinal, as shown and described.
